UNITED STATES PATENT OFFICE.

PRESTON K. ALBRIGHT, OF BINGHAMTON, NEW YORK.

KNOCKDOWN SLED.

No. 821,693.

Specification of Letters Patent.

Patented May 29, 1906.

Application filed August 2, 1905. Serial No. 272,385.

To all whom it may concern:

Be it known that I, PRESTON K. ALBRIGHT, a citizen of the United States, residing at Binghamton, New York, have invented certain new and useful Improvements in Knockdown Sleds, of which the following is a specification.

My present invention relates to improvements in knockdown sleds; and the object of the invention is to provide a sled which may be folded into compact space for shipping and storing, but which when unfolded or set up will have all the attributes of strength, rigidity, durability, and lightness of the ordinary sled.

The invention is illustrated in the accompanying drawings, in which—

Figure 1 is a side elevation, and Fig. 2 a cross-section. Fig. 2^a is a view folded.

In the drawings the runners are shown at 3 and may be made of any suitable material, preferably of metal. They are preferably curved upward and backward, as shown at 3^a, and may very desirably be continued rearwardly as an integral piece to form the side bars 4. Attached to and rising from corresponding points upon each runner are two thin flat bars 5, of steel or other desirable metal, that converge to about their mid-length and then run parallel to each other with a narrow space between. A bracket 6 has a vertically-disposed web 6^a, located between the parallel parts of the bars 5 and secured in place by a rivet 7. Each bracket 6 also has a horizontally-extending ear or lug 6^b, to which the side bar 4 is bolted. The numerals 7' 7^a indicate cross-bars, likewise of metal, to which the board 8 is secured by metal clips 9, which have vertical portions 9^a riveted to the cross-bars and turned-over ends 9^b engaging the edges of the board. Each end of each cross-bar is designed to rest between and be embraced by the ends of the parallel portions of the bars 5, and the web 6^a is located in the proper position to form a stop for the end of the cross-bar to rest upon. Likewise the vertical portions 9^a of the clips 9 are situated so as to act as stops against which the upper ends of the bars or members 5 rest. Additional means, however, may be provided for detachably con-

necting the overlapping ends of the bars 5 and 7', such as bolts 10, passing through alining openings. Inclined braces 11 have their outer ends pivotally connected to and between the bars 5 at or near the point where they diverge. The inner ends of these braces are pivotally connected to opposite sides of the cross-bars 7'. It will thus be seen that when the upper ends of the bars 5 are disconnected from the ends of the cross-bars they may be swung on their pivots and the whole sled folded into the compact position shown in Fig. 2^a.

Having thus described my invention, what I claim is—

1. A knockdown sled comprising cross-bars and runners, standards rising from the runners and having their upper ends detachably connected to the outer ends of the cross-bars, and inclined braces having their opposite ends pivotally connected to the standards and cross-bars, substantially as described.

2. A knockdown sled comprising a pair of runners each curving upward at the front and backward to form an integral parallel side rail, standards rising from the runners and secured to the side rails, cross-bars having their ends detachably connected to the upper ends of the standards, and inclined braces having their ends pivotally connected to the standards and cross-bars, substantially as described.

3. A knockdown sled comprising a pair of runners and side rails, two-part standards rising from the runners, a bracket clamped between the two parts of each standard and connected to the rail, cross-bars having their ends resting between the standards and on said brackets, braces pivotally connecting the cross-bars and standards, a seat-board, and clips clamping said board to the cross-bars and serving as stops against which the upper ends of the standards abut, substantially as described.

In testimony whereof I affix my signature in presence of two witnesses.

PRESTON K. ALBRIGHT.
